(57) **CLAIM**

We claim the ornamental design for an earphone case, as shown and described.

DESCRIPTION

FIG. 1 is a front perspective view of an earphone case, shown in a closed configuration;

FIG. 2 is a front elevation view thereof; and

FIG. 3 is a rear elevation view thereof.

FIG. 4 is a left side elevation view thereof;

FIG. 5 is a right side elevation view thereof;

FIG. 6 is a top plan view thereof;

FIG. 7 is a bottom plan view thereof;

FIG. 8 is a front perspective view of an earphone case, shown in an open configuration;

FIG. 9 is a top plan view thereof;

FIG. 10 is a bottom plan view thereof;

FIG. 11 is a left side elevation view thereof; and,

FIG. 12 is a right side elevation view thereof.

The front elevation view and rear elevation view of the earphone case is the same in the open configuration as the closed configuration.

The broken lines depict portions of the article that form no part of the claimed design.

1 Claim, 8 Drawing Sheets
